[57] CLAIM

The ornamental design for a disposable razor package, substantially as shown and described.

DESCRIPTION

FIG. 1 is a front elevational view of a disposable razor package showing my new design, the rear being substantially a mirror image thereof;

FIG. 2 is an elevational view looking from the left of FIG. 1;

FIG. 3 is an elevational view looking from the right of FIG. 1;

FIG. 4 is a top plan view; and

FIG. 5 is a bottom plan view.

FIG.1

FIG.2
